CLAIM

The ornamental design for a display tomahawk for antennas, as shown and described.

DESCRIPTION

FIG. 1 is a perspective view of a display tomahawk for antennas showing my new design, with the broken line showing for illustrative purposes only and forming no part of the claimed design;

FIG. 2 is a side elevational view, looking from the right in FIG. 1; the left side elevational view (not shown) is a mirror image of FIG. 2;

FIG. 3 is a frontal elevational view;

FIG. 4 is a back elevational view showing mounting screws; and,

FIG. 5 is a top plan view.

FIG. 3.

FIG. 2.

FIG. 4.

FIG. 5.
